Primary Examiner—Robert M. Spear*(74) Attorney, Agent, or Firm*—David E. Wheeler(57) **CLAIM**

The ornamental design for a tire sidewall pattern, as shown and described.

DESCRIPTION

The sole FIGURE is a view of a tire sidewall pattern showing both the pattern and the lettering. In the drawings, the broken lines defining the inner bead of the sidewall and the peripheral boundary between the tire tread and the sidewall are for illustrative purposes only and form no part of the claimed design.
